UNITED STATES PATENT OFFICE.

GEORGE HAYES, OF NEW YORK, N. Y.

WHEEL FOR BICYCLES.

SPECIFICATION forming part of Letters Patent No. 617,743, dated January 17, 1899.

Application filed February 16, 1898. Serial No. 670,494. (No model.)

To all whom it may concern:

Be it known that I, GEORGE HAYES, a citizen of the United States, and a resident of the city, county, and State of New York, have invented a new and useful Improvement in 5 Wheels for Bicycles and other Vehicles, of which the following is a specification.

My improvement relates to the central portion of the wheel; and my invention consists 10 of a construction wherein the axle-hub is resiliently sustained centrally within an encircling spoke-nave by arc springs integral and in combination with spiral coils of approximately tubular shape encircling spin- 15 dles or cross-rods, certain of which extend between end flanges of the axle-nub and others extending between cheeks or end disks of the spoke-nave, all as hereinafter more fully described, and pointed out in the claims, 20 reference being had to the accompanying drawings, in which—

Figure 1 represents a vertical section of the axle-hub, axle, and spindles with inside face, the one end flange of the axle-hub and inside 25 face of the one end cheek or disk of the spoke-nave with one form of arc springs combined with tubular coils. Fig. 2 is a perspective of a portion of springs alone. Fig. 3 is a face elevation of one of the tubular coils with por- 30 tions of arc extensions therefrom. Fig. 4 is an elevation of a spindle or cross-rod. Figs. 5 and 6 are sectional figures corresponding with that of Fig. 1, illustrating changes as to the arrangement of springs, they having 35 been brought wholly within the periphery of the spoke-nave. Fig. 7 is a view correspond- 40 ing to that of Fig. 1, illustrating a change or modification in arrangement of springs, in this case reversed and arching inward, bring- 45 ing the axle-hub against or upon the apex of each arch, the arch being composed of two arc springs joining with one tubular spring interiorly. Fig. 8 is a view of a tubular coil, barrel-shaped, it having convexity lon- 50 gitudinally, otherwise corresponding to those of the previous figures, which are cylindrical. Fig. 9 is a perspective view of the wheel-center, axle, axle-hub, and spoke-nave with arc springs arranged as in Fig. 7 and with the bar- 55 rel-shaped tubular coils of Fig. 8. Fig. 10 is an elevation of a tubular spiral spring, formed of two coils interwoven, one threaded into the

other. Fig. 11 is a perspective view of a tu- 55 bular spiral spring formed double, as that of Fig. 10.

Dotted lines in Figs. 10 and 11 indicate 60 shape of springs when two spirals like that of Fig. 8 are threaded together.

On the drawings, A indicates the axle-hub, 65 inclosing the axle of the vehicle and made in any of the usual forms and preferably ball-bearing.

B indicates the spoke-nave, made as two 70 centrally-apertured cheeks or disks secured together at proper distance apart by cross- rods B', the disks encircling the axle-hub and the hub and nave connected by a system of metal springs, as follows.

C indicates certain spiral coils sleeved upon 75 the cross-rods B' of the spoke-nave, and D 80 indicates other spiral coils sleeved upon cross-rods extending parallel to the axle-hub, be- 85 tween flanges thereof at A' or rings as flanges threaded thereupon, each of the spiral coils being constructed in tubular form and each 90 encircling a cross-rod, which serves as a spin- dle therefor.

E indicates arc-shaped continuance of the 95 metal integral with the coils, as connection-links or stretches between such coils, as shown. The arcs act auxiliary to the coils in securing resiliency between the spoke- 100 nave and axle-hub.

In Fig. 1 the arcs are so formed as to extend 105 beyond the periphery of the spoke-nave.

In Figs. 5, 6, and 7 the arcs are shown as 110 wholly within the area of the spoke-nave.

In Fig. 7 every two arcs, which extend from 115 spindles of the spoke-nave to and are in union with one coil at the axle-nub, constitute, es- 120 sentially, an arch with a resilient key-block, (which is the tubular coil,) and thus the axle- hub is essentially within arches and resting upon the apex of each.

The arrangement of springs in Figs. 5 and 125 6, though different, produces, essentially, the same effect. The arrangement of Fig. 1 brings the axle-hub to rest, essentially, against the bases of the arcs and produces as to the spoke- 130 nave the aspect of its being suspended.

Fig. 4 shows one of the spindles G, having 135 sleeved thereupon flanged washers H. The spindles serve as cross-rods, those of the spoke-nave holding the cheeks or disks there-

of at the proper distance apart, which permit of their faces sliding readily against (without binding) the flanges A' of the axle-hub, which flanges serve to guide the movement 5 and also to prevent any lateral movement.

The end spirals of the tubular coils, whether cylindrical or barrel-shaped, encircle the washers H, and those between are thus held from direct contact with the spindle which 10 they encircle, enabling ready contraction and expansion of the spirals. The wind of the spirals is formed somewhat open to also allow freedom of movement and afford slight twist, whereby effective resiliency is secured therein. 15 The resiliency is supplemented by the springing of the arcs E by their own natural reaction and also by the extended tightening, and consequent resistance, of the coils as the arcs give under pressure produced by weight 20 carried or shock received.

In Figs. 10 and 11 a tubular coil is shown wherein two spirally-wound wires are threaded together, which when placed upon a spindle operate like those before mentioned. In 25 this formation the double arrangement constituting two sets, as in Fig. 9, would not be necessary and the tubular coil would extend the length of the spindle upon which it was placed, and each coil so formed would have 30 four arc ends or stretches, as links, extending to other coils after the manner shown. This arrangement has, perhaps, a more equable effect and is applicable to either the cylindrical or barrel shaped springs.

35 What I claim as new, and desire to secure by Letters Patent, is--

1. A wheel for bicycles and other vehicles formed with a hollow or skeleton spoke-nave, constituted as two disks, centrally apertured,

arranged parallel and connected by cross-rod^s 40 or spindles, with within the same and extending through the disk-apertures, an axle-hub provided with annular flanges with which the disks of the spoke-nave are in facial contact, and between which extend cross-rod^s or spin- 45 dles parallel to those of the spoke-nave, upon each of the spindles of spoke-nave and axle-hub, a tube or cylindrical wind of wire, as a spiral spring, with stretches or continuations of the wire extending in the arc shape to other 50 spiral springs, thus connecting the springs of the spoke-nave with those of the axle-hub, whereby a resilient action is secured, essen- 55 tially as set forth.

2. In a wheel for bicycles and other vehicles 55 constructed with a special spoke-nave encircling an axle-hub, the series of arc-shaped springs, continuations from tubular coils upon spindles of the spoke-nave, extending beyond the periphery of the spoke-nave and 60 converging inward toward the axle-hub, as lines radiating therefrom and connected integrally with tubular coils upon spindles of the axle-hub, essentially as set forth.

3. In a wheel for bicycles and other vehicles, 65 a special spoke-nave encircling an axle-hub, each provided with series of cross-rod^s or spindles, with upon each spindle a spirally-coiled tubular spring of wire formed between its lateral extremities with convexity, the 70 springs of axle-hub and spoke-nave connected by stretches of wire integral therewith, essen- 75 tially as set forth.

GEO. HAYES.
